UNITED STATES PATENT OFFICE.

FLORENCE HARGRAVES, OF FOSTER, CALIFORNIA.

SHOCK-ABSORBER FOR SHIPPING AND STORING RECEPTACLES

1,147,628.

Specification of Letters Patent. Patented July 20, 1915.

Application filed July 13, 1914. Serial No. 850,717.

To all whom it may concern:

Be it known that I, FLORENCE HARGRAVES, a citizen of the United States, residing at Foster, in the county of San Diego and State 5 of California, have invented certain new and useful Improvements in Shock-Absorbers for Shipping and Storing Receptacles, of which the following is a specification.

My invention relates to a shock absorbing 10 attachment for shipping and storing receptacles and resides mainly in the provision of a simple and inexpensive device which is adapted to be attached to the corners of trunks and other shipping and storing receptacles so that shocks incident to rough 15 handling of the receptacles while in transportation and being stored, are taken up and injury to the contents of the receptacle or to the receptacle itself is prevented.

20 An important object of my invention is to provide a device of the character described which may be attached to the corners of shipping and storing receptacles of all characters in a reliable and expeditious manner 25 without necessitating much labor and any material change of the construction of the device to which it is attached.

Another important object of my invention 30 is to provide a device of the character described which is extremely simple as to construction, not liable to accidental derangement, arranged to be fastened upon receptacles so that shocks and jars are distributed evenly with respect to the receptacle 35 and which is cheap to manufacture.

The above and additional objects are accomplished by such means as are illustrated in the accompanying drawings, described in the following specification and then more 40 particularly pointed out in the claims which are appended hereto and form a part of this application.

With reference to the drawings, wherein I have illustrated the preferred embodiment 45 of my invention as it is reduced to practice, and throughout the several views of which similar reference numerals designate corresponding parts, Figure 1 is a fragmentary side elevation showing my shock absorbing 50 attachment attached to the corners of a trunk or like receptacle, Fig. 2 is a sectional view taken through the corner of a receptacle showing my attachment in operative position, Fig. 3 is a sectional view of the corner clamp employed for securing my device upon a receptacle and showing the attach-

ment in elevation, and Fig. 4 is a longitudinal sectional view taken through my shock absorbing device showing the detail construction thereof.

Referring to the drawings, the numeral 1 designates as an entirety a trunk or like shipping and storing receptacle to the corners of which are secured a plurality of my attachments which in Fig. 1 are designated 2 60 as an entirety.

My improved shock absorbing device consists of a cylindrical body portion 3 having one edge reduced to provide a shoulder 4 and being provided with internal screw threads at its other end. Slidably mounted within the cylindrical tubular body portion 3 is a plunger or bumper member 5 provided with a semi-spherical or convex outer face 6 and being enlarged at its inner end 70 to provide a shoulder 7 that is arranged to coöperate with the shoulder to prevent outward movement of the bumper or plunger 5 relative to the body portion 3.

A cylindrical cap 8 having a curved closed 75 end 9 and being provided at its open end with external screw threads 10 is adapted to be turned into the internally screw threaded end of the cylindrical body portion 3.

Mounted within the body portion 3 and 80 cap 8 which is hollow is a helical expansion spring 11 having one of its terminals disposed within a circular recess 12 formed in the inner face of the plunger or bumper 5 and its other terminal disposed in bearing 85 engagement with a ball bearing or other suitable spherical member 13. The bearing 13 engages the curved inner face of the rounded closed terminal 9 of the cap 8. It will thus be seen that when the plunger 90 or bumper 5 is moved inwardly that the movement is against the action of the spring 11 thus causing an absorption of a shock or jar. The tension of the spring 11 may be adjusted as will be readily observed by the 100 turning of the cap 8. The provision of the spherical bearing 13 enables a firm bearing for the spring 11 at all times when the cap 8 is being turned or arranged in different adjusted positions.

105 As a means for securing the device to a trunk or other shipping and storing receptacle there has been provided a corner bracket consisting of a ring like body portion having formed integral therewith a plurality of angular securing ears 15 which are arranged to be secured to the side wall and

bottom of the receptacle and are provided with apertures 16 through which suitable fastening means may be inserted for the purpose of securing the ears. The shoulder 4 formed on the body portion 3 provides an exterior inclined face 17 that is arranged to coöperate with the inclined inner face 18 of the ring like body portion 14 so that outward movement of the device is prevented relative to the corner clamp.

In securing the device an angular opening 19 is formed through the corner of the receptacle 1 and is designed to receive the cylindrical body portion 3 of the device.

15 The plunger or bumper member 5 is arranged to extend beyond the ring-like body portion 14 of the corner clamp so that the engagement thereof with a platform, floor or the like is provided when the receptacle is 20 being roughly handled.

As a means for holding the device so that the outer curved face of the plunger or bumper 5 is extended beyond the corners of the receptacle 1 there has been provided 25 clamping or securing means that is designed to be arranged interiorly of the receptacle 1 at the corners thereof and consists of a semi-spherical body portion 20 having angular apertured securing ears 21 formed integral 30 therewith and adapted to be secured upon the adjacent walls of the receptacle. The body portion 1 is arranged in registration with the inner end of the opening 19 and is adapted to receive the cap 8 and in being 35 semi-spherical conforms to the shape thereof. It will be readily seen that inward movement of the device is prevented by its engagement with the semi-spherical body portion 20 of the clamps or securing means 40 described.

In use the receptacle is equipped at the corners with the shock absorbing means described and secured after the manner described by the clamping means thus when 45 the receptacle is thrown about a floor or platform the shock is taken up by inward movement of the plungers 5 against the action of the springs 11 and injury to the receptacle or the contents thereof is eliminated.

50 It will be readily seen with reference to the foregoing description and accompanying drawings that my shock absorbing attachment may be readily attached to shipping and storing receptacles of all characters and that injury to the contents of the receptacles or to the receptacles themselves is prevented.

The springs 11 may be regulated so that the tension thereof is varied by the turning 60 of the cap 8 as previously described. The whole device may be readily assembled and disassembled so that renewal of parts that may have become worn is readily provided. It will also be readily seen that the device 65 may be attached to the corners of a trunk

or like receptacle in such a way that the general appearance of the receptacle is not marred and construction thereof is not altered to any extent.

In reduction to practice, I have found that 70 the form of my invention, illustrated in the drawings and referred to in the above description, as the preferred embodiment, is the most efficient and practical; yet realizing that the conditions concurrent with the 75 adoption of my device will necessarily vary, I desire to emphasize the fact that various minor changes in details of construction, proportion and arrangement of parts may be resorted to, when required, without sacrificing any of the advantages of my invention, as set forth.

What is claimed is:—

1. In a device of the character described the combination with a shipping and storing 85 receptacle of a cylindrical body portion, a plunger slidably mounted within the body portion and extending beyond one end thereof, means for preventing withdrawal of the plunger from the body portion, a semi-spherical cap adjustably mounted within the body portion at the end thereof farthest removed from the plunger, a helical expansion spring mounted within the cap and body portion, a spherical member mounted between one end of the spring and inner curved face of said cap, the other end of said spring being disposed in engagement 90 with the plunger, said receptacle having an opening formed in one corner thereof, said 100 body portion being positioned within the opening and means for securing the body portion within said opening so that the plunger is disposed in extended relation to the corner of said receptacle.

2. A shock absorber for shipping and storing receptacles comprising a body portion having one end reduced to provide a shoulder, a plunger mounted within the body portion and extending beyond one terminal thereof, said plunger having a shoulder arranged to coöperate with the shoulder on said body portion to prevent withdrawal of said plunger, a cap upon the body portion, a spring mounted within the body portion, a bearing member interposed between one terminal of the spring and the inner face of the cap, and said plunger having its inner face recessed to receive the other terminal of said spring.

3. A shock absorber for shipping and storing receptacles comprising a cylindrical body portion having one end reduced to provide a shoulder, a plunger mounted within the body portion and extending beyond one terminal thereof, said plunger having a shoulder arranged to coöperate with the shoulder on said body portion to prevent withdrawal of said plunger, a cap adjustably mounted within the body portion, a

- spring mounted within the body portion, a bearing member interposed between one terminal of the spring and the inner curved face of the spherical cap, and said plunger 5 having its inner face recessed to receive the other terminal of said spring.
4. The combination with a shipping and storing receptacle having openings formed in the corners thereof of shock absorbing 10 means mounted within each of the openings and extending beyond the ends of the said receptacle to engage the floor or support in advance of the receptacle, said shock absorbing means comprising a cylindrical 15 body portion, a plunger slidably mounted within the body portion and arranged to extend beyond one end thereof, a semi-spherical cap adjustably mounted within the body portion, an expansion spring arranged with- 20 in the body portion, a spherical member interposed between and engaging one end of the spring and the inner curved face of said semi-spherical cap, the other end of said spring being disposed in engagement with 25 the inner face of said plunger, means mounted within the interior of the receptacle for preventing inward movement of said shock
- absorbing means and means secured exteriorly of the receptacle for holding said shock absorbing means against outward movement relative thereto. 30
5. In a device of the character described the combination with a receptacle having openings in the corners thereof, of shock absorbing means arranged in the openings and 35 adapted to extend beyond the outer ends thereof to engage a floor or platform in advance of the receptacle, means mounted interiorly of the receptacle for preventing inward movement of the shock absorbing 40 means and means carried upon the exterior face of the corners of the receptacle for preventing the outward movement of the shock absorbing means whereby said shock absorbing means is disposed to engage the floor or other supporting surface in advance of 45 the receptacle.

In testimony whereof I affix my signature in presence of two witnesses.

FLORENCE HARGRAVES.
